UNITED STATES PATENT OFFICE.

FLORENCE S. CAVANAUGH, OF NEW YORK, N. Y.

DESIGN FOR A BOTTLE.

Application filed May 31, 1927. Serial No. 22,251. Term of patent 7 years.

To all whom it may concern:

Be it known that I, FLORENCE S. CAVANAUGH, a citizen of the United States, residing at 260 West End Avenue, in the borough of Manhattan, city, county, and State of New York, have invented a new, original, and ornamental Design for a Bottle, of which the following is a specification, reference being had to the accompanying drawings, forming a part thereof.

I claim:

The ornamental design for a bottle, substantially as shown.

FLORENCE S. CAVANAUGH.
